BORIS PORT, OF NEWARK, NEW JERSEY.

SPOOL STAND.

Application filed October 15, 1926. Serial No. 141,684.

The invention relates to spool stands, and particularly to spool stands for household and similar use where a short length of thread of one kind or another is frequently 5 in demand, although the invention is not confined to such use. It can be used in many places, for sewing thread, darning cotton, twine or cord and anything else to which it is adapted.

10 The objects of the invention are to provide a spool stand wherefrom the desired kind and length of thread may be most conveniently secured; to enable drawing the exact length of thread desired and no more; 15 to prevent additional thread being drawn when attempting to sever the length desired; to provide means for gripping the thread after the desired length is drawn; to permit the user to draw the thread, cause 20 the thread to be gripped and cut the thread by use of one hand and without change of hold on the thread; to provide a thread cutter upon which one will not cut his fingers; to enable a plurality of spools to be assembled 25 without their various thread ends becoming tangled; to provide a compact arrangement of parts with a neat and convenient assembly thereof in a case; to retain the one spool being used in its proper 30 relation to the cutter; to secure simplicity of construction and operation, and to obtain other advantages and results as may be brought out by the following description.

Referring to the accompanying drawings, 35 in which like characters of reference indicate the same parts throughout the several views,

Figure 1 is a plan of a spool holder embodying my invention, the cover for the case 40 not being shown;

Figure 2 is a side elevation of my invention, partly in central vertical section;

Figure 3 is a perspective view of the preferred construction of the guiding and gripping means;

Figure 4 is a similar perspective view of a modified construction of guiding and gripping means.

Figure 5 is a face view of the thread cutter, and

Figure 6 is an underneath view of the spool-carrying table showing its positioning notches.

In the specific embodiment of the invention illustrated in said drawings, the refer-

ence numeral 1 indicates a suitable base, which in this instance is shown as the lower section of a case having a hinged lid 2 thereto. Any suitable base may, however, be employed. Rotatably mounted on said base, as by a pivot or bolt 3, is a rotary table 4 which is preferably circular with the pivot or bolt 3 concentric therewith. Upstanding from this table at the central part thereof, I have shown a cylindrical housing 5 which receives at its top a removable pin cushion 6 forming a removable closure for said housing. Within the housing is provided an appropriate support 7 for a thimble 8.

Likewise upstanding from said table are 70 a plurality of spindles 9 of suitable size and length to receive spools of thread 10 thereon with proper degree of freedom to enable the spools to be easily turned in pulling thread therefrom. In the present disclosure I have 75 shown several of said spindles arranged in a circle upon the table, but the number and arrangement are not confined to the exact disclosure of the drawings which are for 80 illustrative purposes only.

Preferably opposite the spindles at the 85 edge of the table and upstanding in parallel relation with said spindles, are a plurality of supports, one to each spindle, and here shown as sheet metal extensions 11 turned up from the edge of the sheet metal table. The upper ends of said supports are shown 90 curled over to provide trunnion supports 12 for guiding and gripping means 13, next to be described.

The guiding and gripping means, reference 95 now being had more particularly to Figures 1, 2 and 3, is shown to be a device which, by gravity or otherwise, normally rests in one position, which in the present showing is horizontal, but may be swung out of that position by angular tension on the thread guided by said means. For utilization of gravity, I have shown said means as comprising a lever with a long arm 14 and 100 a short arm 15, a transverse trunnion pin 16 being provided therebetween and supported in the trunnion supports 12 above-mentioned. A stop 17 is provided above the short arm of the lever which is arranged 105 preferably to prevent further swing of the lever when it arrives at substantially a horizontal position. The thread is suitably guided so as to pass along the surface of the lever where engaged by the stop, which ac- 110

cordingly applies a holding tension on the thread when the lever is in engagement with the stop, but will entirely remove that holding tension when the lever is swung away from engagement with the stop. In the figures now being described, the lever is shown with a tapered tubular long arm 14 which provides strength, weight and appropriate guiding means. The inner end or short arm 5 of the lever is shown flat so as to obtain an extended surface for catching the thread against the stop, and an upturned end with a hole 18 therein for guiding the thread to always be between the guiding flat portion 10 of said lever and the stop. For ease in threading through said hole, the metal forming said upturned end may be diagonally slit as shown or otherwise arranged to provide a restricted opening 180 to the hole 18 15 for lateral entry of the thread into said hole. As a further constructional feature of the showing being described, the upper ends of said supports are curled outwardly in the direction of the long arm of the lever, and 20 the stop is mounted on the other or inner side of the support, thereby securing sufficient distance between the trunnion of the lever and the stop to obtain appropriate leverage. It may also be here noted, that 25 the said supports are preferably substantially the height of the usual spool of thread which positions the lever adjacent the upper end of the spool.

A single cutter for all of the threads carried by the spools on the table is preferably employed. In the present showing, the cutter comprises a razor blade 19 suitably mounted in fixed position relative to the spool table at one side of the base 1 opposite the table. Any appropriate clamping means 20 may retain said blade in place against a rest 201, and said rest preferably has a V-shaped guideway 202 in its upper edge to guide the thread downward to a slit 203 across which the edge of the blade 19 extends. By this construction, the thread is readily brought into engagement with the cutter and yet one's fingers cannot come into contact with said cutter, so that there is no danger of injury. Obviously, the blade 19 50 may be placed at any suitable angle or elevation found desirable in constructing the invention. The table is, as indicated, rotatable, so that any spool desired may be brought around next to the cutter, and the thread drawn for the desired length from the spool and then swung down against the cutter for severing the thread.

In order to hold the table against rotating inadvertently I preferably provide a 55 spring detent operating between the base and the table which will hold the table until positively moved from its position. In the present disclosure, said detent is shown as a resilient wire arm 21 with a shoulder

engaging in a notch 22 in the table and with one end secured to the base, said arm being so shaped that pressure on the free end thereof releases said shoulder from the notch, but it can be of any other suitable 70 form or construction.

In operation, the table is turned so that the spool of thread desired is the one next to the cutter. The end of the thread is normally left threaded through the guiding and gripping means so the end of the thread is accessible and readily taken hold of by the user. The user thereupon draws upon the thread, applying the tension in an upward direction sufficient to raise the guiding and gripping lever away from its normal or horizontal position, thus releasing the gripping action of the stop and lever arm on the thread. While pulling on the thread in this fashion, as long a length as desired may be drawn off, and when enough is had, the end being pulled on is naturally swung down so as to engage the other end of the thread with the cutter. That lowering action results in the guiding and gripping lever 80 swinging back to normal position, and as soon as it does so, the thread is gripped between the short arm of the lever and the stop. Then as the user pulls downwardly on the thread to engage it with the cutter, the additional tension exerted will cause the thread to be even more securely gripped, and with the thread thus held taut, it is readily severed when brought into contact with the cutter. Obviously the entire operation is 90 one which is quite instinctively performed by the operator, and requires no particular attention or thought and use only of the one hand holding the end of the thread.

I deem it within the scope of the invention to alter many of the mechanical embodiments, it being appreciated, for instance, that the gripping of the thread might just as well be between a stop for the long arm of the lever instead of the short arm.

Illustrative of these specific variations, I have shown a lever 23 in Figure 4 having a long or heavy arm 24 and a short or relatively light arm 25 with intermediate pivoting means such as trunnion pin 26 passing through depending ears 27 on said lever, said pin being carried by suitable inturned ears 28 on a support 29. The end of the support then acts as a stop, and the thread is suitably guided as through holes 30, 31 105 and 32 to lie between the long lever arm 24 and the upper end of said support or stop.

It will be noted that after the thread has been cut off the end projecting from the guiding means remains held or clamped 115 thereby, so that it is ready to be grasped and released by upward movement when another needleful or other portion is wanted. Such holding or clamping prevents any possibility of the ends from different spools be- 120 130

coming drawn out further or tangled together, inadvertently, and ensures that they are always in place and in order. Furthermore, the clamping or holding is secured automatically, when the thread is cut, gravity in the case of the swinging guide and gripping means causing them to remain in downward gripping position.

Obviously other detail changes and modifications may be made in the construction and use of my improved spool holder, and I do not wish to be understood as limiting myself to the exact constructions shown or specifically described, except as set forth in the following claims when construed in the light of the prior art.

Having thus described the invention, what I claim is:

1. A spool stand comprising means for supporting a spool, a cutter, and a gripping lever between said spool-supporting means and cutter to which the thread is slidably secured longitudinally thereof, said cutter being so disposed with respect to the gripping lever as that when the free end portion of the thread is swung toward the cutter the gripping lever grips the thread before it engages the cutter.

2. A spool stand comprising means for supporting a spool, a horizontally disposed gripping lever to which the thread is slidably secured longitudinally thereof, and a stationary cutter at the opposite end of said gripping lever from said spool-supporting means and low enough so that when the free end portion of the thread is swung toward the cutter the gripping lever grips the thread.

3. A spool stand having means for gripping the thread from said spool, said means comprising a lever pivoted intermediate its

ends with one arm adjacent said spool and having means for guiding the thread along said lever beneath the same, and a stop for gripping the thread between itself and said lever, said stop being positioned beneath the arm of said lever farthest from the entry of the thread from the spool.

4. A spool stand having means for gripping the thread from said spool, said means comprising a lever with one arm heavier than the other and having means for guiding the thread along said lever beneath its heavier arm, and a stop beneath said heavier arm for gripping the thread between itself and said lever.

5. A spool stand having means for gripping the thread of a spool, said means comprising a stop, a lever normally engaging said stop by gravity, and means for guiding the thread between said stop and lever and connecting it to the latter to move up and down therewith, whereby the thread is released by swinging its free end upward.

6. A spool stand having means for gripping the thread of a spool, said means comprising a stop, a lever normally engaging said stop by gravity, means for guiding the thread between said stop and lever and connecting it to the latter to move up and down therewith, and a cutter lower than the lever positioned to be engaged by the thread beyond said lever.

7. The combination with a spool support and a cutter, of an intermediate gripping lever having at its opposite ends means for threading the thread therethrough and exposing it between said opposite ends, and a fixed stop for engaging the thread where so exposed upon the gripping lever.

BORIS PORT.
